US00D866582S

(12) **United States Design Patent** (10) **Patent No.:** **US D866,582 S**
Chang et al. (45) **Date of Patent:** **** Nov. 12, 2019**

(54) **DISPLAY SCREEN OR PORTION THEREOF WITH A GRAPHICAL USER INTERFACE FOR MESSAGING**

(71) Applicant: **Google LLC**, Mountain View, CA (US)

(72) Inventors: **Mark Chang**, Seattle, WA (US); **Matthew Austin**, Palo Alto, CA (US); **James Buyayo**, San Francisco, CA (US); **Jason Cornwell**, Menlo Park, CA (US); **Debbie Kim**, Kirkland, WA (US); **Richard Lo**, Fremont, CA (US); **Johnathon Schlemmer**, San Ramon, CA (US); **Christopher Tompkins**, Mountain View, CA (US); **Megan Torkildson**, Mountain View, CA (US); **Joy Barlow**, Mountain View, CA (US); **Anton Volkov**, San Francisco, CA (US)

(73) Assignee: **Google LLC**, Mountain View, CA (US)

(***) Term: **15 Years**

(21) Appl. No.: **29/642,089**

(22) Filed: **Mar. 27, 2018**

(57) **CLAIM**

The ornamental design for a display screen or portion thereof with a graphical user interface for messaging, as shown and described.

DESCRIPTION

FIG. 1 is a front view of a display screen or portion thereof with a first embodiment of a graphical user interface for messaging showing the new design; and, FIG. 2 is a front view of a display screen or portion thereof with a second embodiment of a graphical user interface for messaging showing the new design.

The dashed broken line showing of a display screen or portion thereof with a graphical user interface is included for the purpose of illustrating portions of the article and forms no part of the claimed design.
